Application April 12, 1922, Serial No. 551,971

12 Claims. (Cl. 282—16)

This invention is in some of its aspects a continuation of my copending application No. 452,512, filed March 15, 1921.

This invention relates to a manifolding machine adapted to make a manifold record on duplicate forms, and particularly to such machines having a mechanical or automatic feeding mechanism.

An object of the invention is to provide a simple, inexpensive and compact machine of the class described, which shall be convenient to operate, and simple, accurate and reliable in its functioning.

Other objects of the invention will be in part obvious and in part pointed out hereinafter.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which—

Figure 1 is a plan view of the machine;

Fig. 2 is a central vertical longitudinal section of the machine;

Fig. 3 is a cross section in the line 3—3 of Figure 1;

Fig. 4 is a cross section in line 4—4 of Figure 1; and

Fig. 5 is a plan view of a portion of one of the strips employed.

Referring to the drawings in detail and particularly to Figures 1, 2 and 3, the character "A" indicates in general a casing consisting of a bottom section 2, a pair of side sections 3, a stationary end section 4 and a pivotally mounted end section 5. Mounted between the casing within the side plates for the purpose of forming the compartments indicated at 7, 8 and 9 is a pair of transverse plates 6, and forming a closure for the several compartments is a writing tablet or plate 10, a cover 11, and a second cover 12. The cover 11 is disposed above the compartment 9 and is hingedly supported on one side of the machine as at 13. The cover 12 forms a closure for all of the compartment 7 and in part for the compartment 8, it being also supported by being hinged on one side as at 14. The cover section 11 is cut out as at 15 to expose the writing tablet or plate 10 over which the sheets to be written on are passed during the operation of the machine.

These sheets are preferably made in the form of a single pad to supply all of the copies of the record desired in the machine. By thus furnishing a unitary web supply the replacement of the sheets in the machine is accomplished with a maximum of ease. The sheets are arranged in the supply in sets adapted to be fed together over the tablet, the sets being connected together end to end to form a composite traveller strip, each strip of which forms one leaf of each set.

In the making of a plurality of copies it is desirable that the sheets for receiving the record have forms printed thereon to assist in the interpretation, and it is desirable that the machine shall be adapted to insure that the forms of a given set are in registry with each other as they pass over the tablet. By providing the webs in a unitary pad the maintenance of registry is facilitated by reason of the fact that the delivery of one sheet from the pad assists in the delivery of the others. In order that the sheets may be brought into proper registry upon the tablet means are provided whereby the feed itself is determined by the sheets and to this end the web is provided with a recurring characteristic bearing a definite relation to the printed form and the feed is designed to cease functioning in response to that characteristic.

As illustrated, three separate strips 16, 17 and 18 are provided which are overlaid in the supply, being superposed upon each other and reversely interfolded in zigzag formation. Each of these sheets preferably has the forms printed thereon successively and feed control apertures similarly placed with regard to the leaves bearing definite relation to the printed forms. With this form of book the forms will be maintained in registry in the book, and may be fed in registry over the tablet. The sheets of the pad B preferably bear one form upon each sheet and the strips may be weakened between the sheets to facilitate separation.

The feeding mechanism is adapted to feed the sheets until its operation is limited by the recurring characteristics. As illustrated, it comprises, a mechanism, adapted to frictionally engage the sheets in longitudinal alignment with the perforations, but having an area of contact with the sheets less than the area of the perforations, whereby the feeding operation will stop when the feeding mechanism comes opposite the perforations.

The manifold book or pad illustrated at B, see Fig. 2, is placed within the container or chamber 9 by opening the hinged end section 5. The sev-

eral strips are then passed between a series of separating and tension rollers 22, 23 and 23a, and are then passed over a series of guide rollers such as shown at 24, 25 and 26. The sheets are then passed over the writing pad or plate 10 as shown in Fig. 2, and are finally passed beneath a spring pressed feed roll 27. The roller 27, see particularly Figures 2 and 3, is carried by a locking bar 28. A pair of vertically disposed self-adjusting bearing members 29 supports the roller, that is the journals are vertically movable with relation to the locking bar, but they normally hold the roller 27 in a projected position as springs 30 are interposed between the inner ends of the journals and the bar. Extending crosswise of the machine, and centrally of the chamber 8, is a shaft 31. This shaft is rotatably mounted in journal members 32 formed in the respective side plates. Secured on the shaft within compartment 8 is a pair of feed rollers or disks 33 and 34. These strip feeding discs cooperate with the roller 7 when rotated to simultaneously feed the several strips of the manifold pad in a forward direction over the writing tablet as will herein-after be described.

The feed mechanism just described is adapted to grip the strips or webs between the resilient roll and the disks, and thereby to advance the composite strip as the feed is operated until it becomes ineffective to advance it further by engagement with an aperture in the strip. Thereupon by reason of the fact that the contact between the disk and the roll is of less area than the aperture the feeding ceases. The different sets can thus be brought successively over the said tablet with the leaves in superposed relation, and in registry. Moreover the feed mechanism employed and the type of pad employed cooperate to insure that the sheets are fed from the supply in unison, thus facilitating their being fed over the tablet in registry. The strips are moreover separated as they leave the pad and are preferably maintained substantially independent of each other by being kept out of contiguity substantially to the point where they pass over the tablet, in order that they may be fed over the transfer sheets without difficulty. They are, however, maintained in proper juxtaposition so that they may be readily maintained in registry by the feeding mechanism.

Secured on the outer end of shaft 31 is a hand actuated crank 35. Disposed in the arc of movement of said crank is a pin 36. This pin is normally projected by a spring 37, but may be depressed when it is desired to rotate the crank. The locking bar 28 is pivotally attached to one of the side plates as indicated at 38 so that it may be opened and closed. It is however locked in position with relation to the feeding disks 33 and 34 when lowered by means of the latch and keeper indicated at 39 and 40, respectively. The latch 39 is adapted to be moved into and out of engagement with the keeper through means of a push button 41. The button 41 is provided with a pin extension 42 as is also the latch 39; the pins on the respective members being tied together by a connecting bar 43. A spring 44 interposed between the button and the inner end of the recess in which it is guided normally retains the latch in engagement with the keeper and similarly retains the button in a projected position. Therefore if it is desired to release the locking bar 28, it is merely necessary to depress the button. Conversely, if it is desired to lock the bar it is mere-

ly necessary to depress it until engagement is made between the latch and the keeper when it is automatically locked.

The feeding disks 33 and 34 are connected by a cross bar 45, see Fig. 3. This bar carries a pair of feeding lugs 46, one disposed at each end thereof, and it also insures unitary rotation of the disks. Radially disposed in a seat in the disk 34 is a registering pin 47 which is automatically projected by means of a spring 48. The position of the pin is however normally depressed and it is retained in this position by means of a latch 49, which is carried by a pin 50, surrounded by a spring 51, the spring normally maintaining the latch in locked position. The means herein disclosed for depressing or retracting the pin 47 after projection thereof by the spring 48 embodies the feed roller 27 mounted upon the swinging locking bar 28. Thus, to effect pin retraction the raised locking bar 28 is swung downwardly carrying the roller into its strip feeding position and into contact with the projected pin so as to retract the latter causing it to be latched in its depressed position by means of the latch 49.

The pin 50 aligns with the connecting bar 43 and is engaged thereby when the button 41 is depressed, that is, depression of button 41 does not only serve the function of releasing the keeper 40 of the locking bar 28, but it also imparts endwise movement to the pin 50 and the latch 49 carried thereby, thus simultaneously releasing the registering pin 47 when the locking bar is released.

Individual strips of the manifold pad are, as previously stated, advanced over the surface of the tablet 10. They are only intermittently advanced, that is a set of aligned forms is brought into register with the writing opening 15 of the cover 11 where the printed form of the topmost strip is filled in by writing or otherwise. One of the features of the present invention is to provide means for insuring correct register of the printed forms on the underlying strip and to insure transfer in registration of the matter written or otherwise applied to the uppermost form. In effecting this transfer a series of transfer sheets such as generally indicated at C is employed. These sheets are disposed in roll formation in a pocket 60 formed in one of the side plates. There may be two or more separate transfer sheets in a roll and these are disposed transversely with relation to the record strips so that they may be interleaved with relation thereto. As the transfer sheets may be employed a considerable number of times before change or advancement thereof is required, means for securing their free ends is provided. This means consists of a spring actuated rod 61, which cooperates with a recess in the cover indicated at 62. The rod cooperating therewith forms a spring clamp or detent which secures the free ends of the sheets, thus preventing accidental release or movement of the same when the manifold strips are being advanced to bring a new set of forms in writing position.

In actual operation if it is desired to place a manifolding book or pad in the compartment 9, the locking bar 28 is released; by merely depressing the push button 41. The locking bar is then swung about its pivot 38 so as to clear the side of the machine and it is then possible to raise the covers 11 and 12. It will be observed that the edge of the cover 12 adjacent to the feeding mechanism projects slightly in under the wall of the locking bar 28, forming the cutting edge 71 whereby said cover is retained 75

in its closed position by said locking bar when the latter has been lowered into its closed or operative position. This cover will also be released to opening movement when the locking bar is raised. This edge of the cover provides a strip separator and diverter as fully described below. A manifold pad as illustrated at B is then placed in compartment 9 and the free ends of the strips are passed upwardly between the rollers 22, 23 and 23a. They are then separated by the rollers 24, 25 and 26, and are advanced over the writing pad until the foremost apertures or punched portions 21 of the strips register with the feeding rolls or disks 33 and 34. Pin 47 stands in a projected position at this time, and to insure alignment of the strips, and particularly registration of the printed forms, the advance aperture in each strip is applied to the pin. When placing the forms in position, the cover 12 may be raised when the first strip is passed over the pin and then closed before the remaining strips are placed. This permits the lowermost of the strips to be passed downwardly into the compartment 7 and the two uppermost strips to be separated with relation thereto by the separating edge 70 formed on the cover, and to be severed when desired the locking bar having been lowered to closed position. Previous to the separation of the lowermost strip from the uppermost strips, it is best to interleave the several strips by passing the transfer sheets between the same. When this has been accomplished, the cover 11 may be lowered and thus secure the free ends of the transfer sheets as indicated at 62. The strips may now be registered by the pin and separation may be accomplished by passing the free end of the lowermost strip into compartment 7. The cover 12 is then closed and the locking bar is finally lowered into position and locked, when the machine is ready for operation.

We will now suppose that the machine is being employed in a store, and that a sale has been recorded by filling in the blank portions of the uppermost form which is disposed in alignment with the writing opening 15. After record of the sale has been made, it may be desirable to give a duplicate to the customer, to provide one or more for files, records, etc., and furthermore to obtain a secret copy which cannot readily be altered or changed. Therefore after the sale has been recorded by writing on the form or otherwise, the crank 35 is turned one revolution. This is accomplished by first depressing the button 36 and then turning the crank; the crank being turned until the button is again engaged. The proportions of the feeding disks 33 and 34 with relation to the length of the printed forms on the strips are such that the written forms will be advanced to the point of discharge, while the succeeding forms will be brought into register with the writing opening. During the advance of the several forms which takes place when the feeding disks 33 and 34 are rotated by means of the crank, the lowermost copy is directed into the secret compartment 7, this being accomplished by forming a sharp lip 70 on the forward edge of the cover section 12. The remaining strips are deflected upwardly by this lip as the upper surface is slightly inclined and they may thus be severed along the weakened lines 20, see Fig. 5, as these will register with a tearing or cutting lip 71 formed on the rear side of the locking bar 28; that is such registry will be obtained when the crank has completed its revolution, or

in other words when the forms have been completely advanced. The uppermost strips containing the forms may then be torn to remove the inscribed sections or leaves for filing or otherwise, while the secret copy is deposited in the compartment 7 where it cannot be tampered with or altered. To further insure against removal of the secret copy, it is obvious that a lock may be employed in conjunction with the cover 12, and that means must be provided for preventing reverse rotation of the shaft 31 and the feeding disks 33 and 34. This is accomplished by securing a ratchet wheel 72 on the shaft which is at all times engaged by a pawl 73, this pawl being spring actuated, constantly engages the ratchet wheel thus preventing reverse rotation of the shaft at all times. As previously stated means are provided for aligning the several strips when they are first placed in position on the writing tablet or plate 10; this being accomplished by projecting the registering pin 47 and placing the apertures 21 over the same. This operation not only provides for alignment of the strips but also insures perfect register of the printed forms, and such registry is automatically maintained once the machine is started, due to the provision of the apertures 21, and is accomplished as follows.

The apertures are in alignment with the feeding disks 33 and 34 and the several strips are fed by the pressure exerted between the roller 27 and the disks. Now it will be perceived that when the apertures come into alignment with the roller 27 and the disks 33 and 34, a void or space will be formed so that the grip on the strip will cease and further movement of the paper arrested with the disks penetrating the apertures. In actual practice it is found that the uppermost strips have a slight tendency to lag, so that the apertures on the lowermost strip will reach the roller 27 first and the apertures on the overlying sheets will lie slightly behind those in the lowermost strip. The feeding disks will therefore advance the uppermost strips until the apertures in the several strips register and the feeding disks 33 and 34 will therefore continue rotating without further advancement of the paper as the grip on the paper may be lost, due to the void or space formed by the apertures. Such continued movement of the feeding disks is however prevented in the present embodiment as the crank 35 will at this time reach the stop member 36 and may not be further rotated until the stop is again depressed. This however should not take place until the advance of the next set of forms is to be started.

It will thus be obvious that the outer periphery of the feed discs should exceed the length of a form by an amount at least sufficient to allow for the adjustment just described.

Lugs 46 are provided at each end of the cross-bar 45 which are arranged to bear upon the strip beside the control apertures to co-operate with the roll 27 to grip and feed the strip at the beginning of the feeding movement, and they are properly positioned relative to the pin 47 to that end. The stop 36 is arranged to arrest the handle 35 while the record sheets are in registry upon the tablet, which will ordinarily be substantially when the pin 47 and the lugs 46 have come opposite the roll 27.

By referring to Fig. 2, it will be seen that the cover section 12 is provided with a curved guide 80 near its forward end and a spring arm 92 which is pivotally attached as at 93. This guide is provided for the purpose of deflecting the

secret copy in a downward direction and the arm serves as a weight, thus insuring proper folding of the copy strip as it enters. It will further be seen that the cover is slotted as at 81 and 82 and that a pair of rollers 83 is journaled under the cover adjacent said slots; said rollers supporting an endless belt 84 which passes under the rollers and out through the slots. The belt is guided on the upper surface of the cover by a rectangular shaped frame 84a. One side of this frame is open to permit a score card or the like to be inserted between the belt and the cover 12 as indicated at 85. The belt proper is transversely slotted as at 86 and is provided with a knob or other projection 87 by which it may be moved lengthwise. The score card remains stationary and may be removed, aligned or otherwise prepared to receive any data desired. For instance a salesman may wish to make a separate record showing the totals of each sale and may wish to indicate such notes on the score card. He therefore moves the belt until the transverse slot 86 registers with the topmost line of the score card. He then writes through the slot and enters the data desired, and then advances the belt until the slot registers with the next line on the card. The sale recorded on the card is thus covered up and cannot be viewed by the general public and the slot is simultaneously moved to the next line where a new sale or other data may be recorded.

Having thus described my invention, what I claim and desire to secure by Letters Patent is—

1. A device of the character described, in combination, a casing adapted to contain a web supply comprising a plurality of strips having forms thereon and control apertures in registry with said forms, a feeding mechanism for advancing said strips, rendered ineffective to advance by engagement with an aperture, said feeding mechanism comprising a pair of feed rolls adapted to engage said strips between them to grip and advance the same, one of said rolls movable toward and from the other, a pin rotative with one of said rolls and reciprocally movable relative to the latter roll transversely of its axis of rotation, and a spring adapted to urge said pin to a position projecting beyond the periphery of said latter roll.

2. In a device of the character described in combination, spaced feeding disks and a radially disposed pin carried by one of said disks, a lock bar transversely disposed with relation to the disks, a pivotal support for said bar, a pair of vertically movable journal members carried by the bar, a roller journaled in said members and engageable with the disks, a locking member for the locking bar, and means actuated by said locking member for projecting the pin on one of said disks.

3. In a machine of the class described, in combination, a casing adapted to contain a web supply comprising a plurality of strips having forms thereon and control apertures in registry with said forms, a tablet, a shaft journaled in said casing carrying disks in alignment with the apertures, a roller above said disks adapted to make contact therewith of less area than the area of the apertures, a resilient support for said roller to retain it in position to advance the strips until an aperture is reached, a pin on one of the disks in position to be projected through said apertures and means for projecting and retracting said pin.

4. In a machine of the class described, in combination, a casing adapted to contain a web sup-

ply comprising a plurality of strips having forms thereon and control apertures in registry with said forms, a tablet, a shaft journaled in said casing carrying disks in alignment with the apertures, a roller above said disks adapted to make contact therewith, of less area than the area of the apertures, a resilient support for said roller to retain it in position to advance the strips until an aperture is reached, a spring pressed pin on one of said disks in position to be projected through said apertures and a latch for retaining said pin in one position.

5. A manifolding device comprising, in combination, a casing adapted to contain a web supply having perforations bearing definite relation to forms printed thereon, feeding mechanism for said forms adapted to feed the web from said supply, a pin projectable into the pathway of said perforations to engage the latter to permit pre-alignment of the web, an element movable to open the feeding means to permit the insertion of the web therein, said pin being adapted to be withdrawn from the pathway of the perforations by the moving of said element to close the feed.

6. In a machine of the class described, in combination, a casing adapted to contain a web supply having perforations in definite relation to forms printed thereon, and means to advance the superposed strips to register the leaves of each set in succession in writing position, said means including a paper-gripping driven disk and an idler roll opposite thereto adapted to cooperate therewith, one of said elements being journaled in a bar whereby it may be moved to and from the other to permit the placing of the paper therebetween, a pin carried by one of said elements movable from a position in the pathway of the perforations to a retracted position, said pin being so associated with said bar that when said rolls are brought together for feeding purposes by the movement of said bar, said pin is automatically retracted out of the path of the strips.

7. In a machine of the class described, in combination, a casing adapted to contain a web supply having perforations in definite relation to forms printed thereon, and means to advance the superposed strips to register the leaves of each set in succession in writing position, said means including a paper-gripping driven disk and an idler roll opposite thereto adapted to cooperate therewith, one of said elements being journaled in a bar whereby it may be moved to and from the other to permit the placing of the paper therebetween, a pin carried by one of said elements movable from a position in the pathway of the perforations to a retracted position, means for locking the same in a retracted position, said pin being so associated with said bar that when said rolls are brought together for feeding purposes by the movement of said bar, said pin is automatically retracted out of the path of the strips.

8. In a device of the class described, in combination, a casing, feeding mechanism including an upper roller, a support for the roller hinged to the casing to swing with the roller out of position to permit threading of the machine, a releasable latch for the support, an aligning pin in connection with the feeding mechanism, a latch for holding the aligning pin in inoperative position, and a common means to simultaneously release both latches.

9. In a device of the class described, in combination, a casing having a holding compartment

for a pad of interengaged reversely folded strips of paper or the like and a receiving compartment for receiving sundry of the strips, a writing tablet between the compartments, means to advance the strips over the tablet, a cover for the receiving compartment, the feeding mechanism including a roller, a locking bar for the cover hinged to the casing, and carrying the roller, and a latch for holding the locking bar in closed position.

10 10. In a device of the character described, a casing, having a compartment formed therein for the reception of a plurality of continuous paper sheets folded in zigzag form, a plate covering said compartment forming a writing tablet, a cover 15 hinged to the casing, to enclose the tablet, said cover having an opening formed therein to permit exposure of a predetermined area of the tablet, paper feeding means disposed at the forward end of the tablet, said means comprising a pair 20 of feeding rolls and a superposed resilient feeding roll, a pivotally mounted bar in which the resilient roll is journaled, a compartment formed in advance of the feeding means, a hinged cover therefor, said hinged cover being disposed below 25 the hinged bar for engagement thereby, and means for locking the locking bar and said covers

against movement away from normal operative positions.

11. In a device of the character described, in combination, a shaft, a pair of narrow inter-spaced feeding disks secured on the shaft, a cross bar connecting the disks, an auxiliary feeding lug disposed at each end of the bar, manually operated means for imparting one revolution to the shaft and the disks carried thereby, means for automatically securing the shaft against more than one revolution, means preventing reversal of the shaft, a feed roll disposed above the disks, a resilient mounting for said roll, a locking bar supporting the resilient mounting and the roll, a pivotal support for said locking bar, and means 15 for locking the locking bar when the roll is in engagement with the disks.

12. An autographic register including, in combination, record strip feeding mechanism including a feed roll, a roll carrier movably mounted 20 to carry said roll to and from strip feeding position, and a strip diverter mounted for movement to and from operative position and retained in operative position by cooperation of said roll carrier.

25 WILLIAM J. WISWALL.
